UNITED STATES PATENT OFFICE.

HUDSON A. TEDMAN, OF GALESBURG, ILLINOIS, ASSIGNOR TO WINSLOW BOILER & ENGINEERING COMPANY, OF CHICAGO, ILLINOIS, A CORPORATION OF ILLINOIS.

LIQUID-FUEL BURNER.

Application filed October 25, 1920, Serial No. 419,252. Renewed March 15, 1923.

To all whom it may concern:

Be it known that I, HUDSON A. TEDMAN, a citizen of the United States, residing at Galesburg, in the county of Knox and State 5 of Illinois, have invented certain new and useful Improvements of Liquid-Fuel Burners, of which the following is a specification, reference being had therein to the accompanying drawing.

10 The invention relates to various novel features in liquid fuel burners, and consists in the matters hereinafter described and then pointed out in the claims.

In the accompanying drawings, which illustrate a tested and practical embodiment of the several features of my invention, Fig. 1 is a plan view of the device partly in section on the line 1—1 of Fig. 2 for convenience of illustration;

20 Fig. 2 is a view in longitudinal vertical section on the line 2—2 of Fig. 1, and

Fig. 3 is a view in perspective with the end of the fire-pot broken away.

In the drawings the reference numeral 10 indicates the air duct connected at its intake end to an air-blower 11 of a type capable of delivering a sufficient quantity of air to ensure perfect combustion, and at its outlet end widened laterally and divided by the 25 V-shaped partitions 12 into two laterally diverging conduits 13 and 14, the mouth of each having a surrounding flange 15 by which it is connected to a corresponding flange 16 on the fire-box 17. By this arrangement the air-supply duct is bifurcated into 30 a pair of branches which deliver the air tangentially into the fire pot in two lateral streams.

The fire-pot or combustion chamber 17 is 40 of any suitable contour in plan section to conform to the design of the steam generator or boiler with which it is associated, and in the present instance I show it as substantially circular. Its bottom plate 18 is flat, and its rear and side walls 19 and 20 are inwardly oblique or slanting, being preferably curved from bottom to top, so that the general contour of the pot is more or less frusto-conical in form and the flame discharge opening 21 at its top is more or less restricted and smaller in diameter than the cross-sectional area of the interior. At the 45 inlet side of the chamber its bottom is extended rearwardly and its sides are correspondingly extended rearwardly and lat-

erally to substantially vertical position, as shown at 22, and the top of this extension is provided with a cover plate 23 which is curved at its inner edge to conform to and extend the curvature of the opening 21 which thereby becomes circular, these parts preferably being made integral and provided with the flange 16 by which the pot is attached to the flange 15 of the air duct. The air inlet of the pot is thus made substantially rectangular in outline with its major axis horizontal and somewhat longer than the diameter of the pot, and a central vertical partition 24 is provided so that the air inlet is itself divided into two legs respectively corresponding with and in extension of the air conduits 13 and 14, and the air is delivered into the pot in two opposite tangential streams at its sides.

The fuel oil is introduced directly into 75 the pot through a nozzle 25 in the partition 24, preferably near its top, from any suitable source of its supply, and falls upon a distributing plate 26 which is located near the bottom of the pot by which it is broken 80 up and splashed into the chamber. This plate is inclined from its rear toward the front of the chamber to throw the oil particles or atoms forward as well as laterally, being supported by its rear flange 27 upon a rib 28 near the partition 24, and resting at its rear edge upon the bottom 18. This plate not only breaks up and spatters the oil into the pot or chamber but also deflects and spreads the igniting flame of a pilot 90 burner 29 which is located beneath it; the burner is preferably provided with an opposite pair of laterally extending jets, as shown, so as to throw the igniting flame into the two lateral streams of inflowing air, and the 95 plate is preferably provided with perforations which allow the oil to drip through and further atomize it in contact with the flame. By this arrangement the igniting flame contacts with the atomized oil to ignite 100 the fuel and start the burner, which continues to burn as long as oil and combustion air are supplied to the pot. The bottom 18 is provided with a drain opening normally closed by a plug 30 to draw off any oil 105 that may escape into the pot while the device is out of operation.

When the fuel oil enters the pot it is broken up into small particles and vaporized more or less by the distributing plate 26 and 110

is further vaporized by the surrounding air streams and currents and mixed with them in the form of a mist that is disseminated throughout the pot and is readily ignited by 5 the pilot flame, it being understood that the blower is then operating to furnish the air necessary to insure complete combustion of the oil, but without sufficient force to overcome the natural tendency of the flame 10 to rise through the top of the pot. The distributing plate is heated by the igniting flame, which may be started to pre-heat it when the pot is cold and which may continue to burn during the inoperative periods 15 of the pot that occur in heating systems which are periodically started and stopped, so that in either case the initial oil falling on it is vaporized by it, and this plate is heated by the combustion of the fuel in the 20 pot and remains hot even if the igniting flame is extinguished during the brief periods of stoppage in the regular operation so that the oil falling on it during the operative periods is vaporized by it. The air 25 passes into the pot in two lateral columns, one at each side of the oil supply, which pass directly into the oil broken up into fine particles and spattered out by the intermediate distributing plate, and further vaporize it 30 and mix with it to form an easily combustible mixture, and the lateral intake of the air, aided by the inward taper of the extensions of the side walls, causes each of the columns or streams of the mixture to assume 35 a gyrating or swirling motion, which is intensified by the curvature of the side and rear walls of the pot toward its rear end, and the inward inclination or curvature of the side and rear walls of the pot toward its 40 central opening aids these two gyrating columns of mixed oil and air to blend into a single central column of flame which fills and projects out of the opening, where it burns with great intensity. In short, two 45 streams of air which mix with the oil to form the combustible mixture flow into the pot, one on each side, and each stream developing into a vertical column of flame rising to or above the top edge of the chamber 50 and uniting to form a single substantially solid or unbroken column of intense flame above and outside of the chamber. The edge of the flame opening is plain or unobstructed so that the tendency of the flame to rise 55 through the opening is not impeded, the opening being contracted to form a central flame exit by reason only of the inward inclination of the sides and front walls of the chamber. I am thus able to dispense 60 with devices for either pre-heating the oil before its delivery to the fire zone or for atomizing or aspirating or spraying the oil and their accompanying high-pressure steam or air supply apparatus to form and project the fuel mixture into the burner, and 65

also with supplemental fuel-enriching or pre-vaporizing or pre-heating devices to initiate the combustion of the mixture. The effects produced by my invention apparently are due to the fact that instantaneous and 70 complete production and commingling of the combustible elements of the fuel take place in the burner under conditions assuring immediate ignition and continuous combustion. This is shown by the fact that in 75 the burner there is no evidence of a rolling flame and no deposit of carbon. The air and vaporized oil are intimately and perfectly mixed in the burner, and the fuel so formed burns with a clean flame that is 80 free from smoke and residuum, and the flame takes a prolonged conical form with its body projecting well out of the burner top in relatively large volume.

I claim:

1. In a liquid fuel burner, a chamber having its walls inwardly inclined to form a relatively restricted flame discharge opening, an air supply device having air-inlets at the sides of the chamber constructed to 90 introduce air into the chamber in lateral streams, and an oil supply between the air-inlets.
2. In a liquid fuel burner, a chamber having a divided air inlet and its walls inwardly inclined to form a relatively restricted flame discharge opening, an oil supply between the air inlet portions, an air supply device having diverging conduits introducing air through said inlets in lateral streams at the 100 sides of the oil supply, and an oil distributing plate below the oil supply.
3. In a liquid fuel burner, a chamber having a side inlet provided with a central dividing plate, and its walls inwardly inclined 105 to form a relatively restricted flame discharge opening, an oil supply at the top of the dividing plate, and an air supply device introducing air through said inlet in a stream at each side of said plate.
4. In a liquid fuel burner, a chamber having a side inlet provided with a central dividing plate, and its walls inwardly inclined to form a relatively restricted flame discharge opening, an oil supply at the top 115 of the dividing plate, an air supply device introducing air through said inlet in a stream at each side of said plate, and an oil distributing plate in the chamber.
5. In a liquid fuel burner, a chamber 120 having a side inlet provided with a central dividing plate, and its walls inwardly inclined to form a relatively restricted flame discharge opening, an oil supply at the top 125 of the dividing plate, an air supply device introducing air through said inlet in a stream at each side of said plate, an oil distributing plate near the bottom of the chamber, and an igniting device below the plate.
6. In a liquid fuel burner, a fire pot hav-

ing an oil supply and air inlets in its side, the air inlets being constructed to pass streams of air into the pot at the sides of the oil supply, the walls of the pot being inwardly curved to form a restricted central opening to permit the flame to rise above the top of the pot, an inclined oil distributing plate below the oil supply and intermediate the air inlets, and a pilot light 10 below the plate.

5

ing a central oil pipe and lateral air inlets in its side, the air inlets being constructed to pass streams of air into the pot at the sides of the oil supply, and the walls of the chamber being shaped to cause the streams of air to form with the oil a combustible mixture and having an unobstructed central opening to permit the flame to rise above the top of the chamber, and an oil distributing plate 15 20 below the oil supply.

7. In a liquid fuel burner, a chamber hav-
